Primary Examiner — Robert M Spear*Assistant Examiner* — Marissa J Cash(74) *Attorney, Agent, or Firm* — Ladas & Parry LLP(57) **CLAIM**

We claim the ornamental design for a drone, as shown and described.

DESCRIPTIONFIG. 1 is a front view showing our new design for a drone.
FIG. 2 is a rear view thereof.FIG. 3 is a right side view thereof; the left side view is a mirror image of the right side view.
FIG. 4 is a top view thereof.

FIG. 5 is a bottom view thereof.

FIG. 6 is a top perspective view thereof from the front.
FIG. 7 is a top perspective view thereof from the rear; and,
FIG. 8 is a bottom perspective view thereof.

The drone can be used as an unmanned air vehicle (UAV) having vertical take-off and landing (VTOL) and linear flight capability as well as the ability to carry loads. The drone can be used as a workhorse drone for lifting, equipment transport, security, and emergency repairs (while carrying tools therefore) in remote and difficult locations.
